UNITED STATES PATENT OFFICE

WILLIAM H. HARRINGTON, OF WEST HARTFORD, CONNECTICUT, ASSIGNEE TO THE ARROW-HART & HEGEMAN ELECTRIC COMPANY, OF HARTFORD, CONNECTICUT, A CORPORATION OF CONNECTICUT

HEATER-CIRCUIT CONTROL

Application filed November 23, 1930. Serial No. 409,390.

This invention has to do with the control of electric circuits in which there are heating elements arranged to be connected electrically in different ways to give different degrees of heat. It provides a switch base which may be used with two different sets of related fixed contacts and switch blades to enable three degrees of heat to be obtained either from a three wire supply having a neutral wire or from a two wire supply. The connections to the heating elements are the same regardless of which set of fixed contacts and switch blades is used. This switch base also has terminals in the form of a receptacle for an attachment plug to which the wires leading to the heating elements are connected.

A preferred form of the invention is here described and is illustrated in the accompanying drawings to which reference is made in the course of the description.

Figure 1 is a top plan view of a switch base having the switch mechanism in place in a well therein but having the thumb piece or actuator broken away.

Figure 2 is a view of the bottom of the same base.

Figure 3 is a side view, partly in section, of this base with the attachment plug, to which the wires leading to the heating elements are connected, in place thereon.

Figure 4 is a side view of the said attachment plug.

Figure 5 is a diagrammatic view of one set of related fixed contacts and switch blades showing the connections of the former to an Edison three wire circuit and to a two-element heater, and showing the blades in their open-circuit or "off" position.

Figure 6 is a similar view showing a set of contacts and switch blades for connecting the same heater to a two wire supply, shown here as being two wires of an Edison three-wire circuit.

Figure 7 is a sectional view of the base

through the switch well about on the line 7—7 in Figure 1.

The base is formed as a block 10 of molded insulating material and has a circular switch well 11 on one side toward one end and a receptacle on the opposite side at the other end. On this opposite side, which will be called the bottom, are three transverse grooves 12^a, 12^b and 12^c, each adapted to receive a bus bar or feed wire of the supply circuit. A rotary switch mechanism is mounted in the well 11. This mechanism is not shown here in detail as it may be of any suitable construction adapted to turn the switch blades in unison with a snap action through steps of 90° each, thus giving four switch positions. There are two switch blades, in the forms shown here.

The spindle of the switch mechanism is supported by a yoke 15 extending across the switch well and made with a hole at its mid point so that it may slip over the spindle, all according to conventional practice. A novel feature however is the extension of the wings or lateral arms 16 at the ends of the yoke so that the holes 17, through which the screws 18 extend to hold the yoke to the base, are 90° apart and are equally spaced. By reason of this the yoke may be placed on the base in such a way that it extends along the long axis of the base, as in Figure 1, or at right angles thereto. Since the yoke serves to mount the switch base on a range or other place of use, the holes 19 at the ends of the yoke being for this purpose, the base may be mounted in either of two positions at right angles to each other.

The fixed contacts are mounted in bays opening to the switch well and thus they are supported on the base and extend into the well. The bays are 90° apart around the well to correspond to the four points with which the switch blade arms register when at rest. These points about the well at which the bays are located will be termed "quarter points" or generically, "switch points" since they are

the points at which the fixed contacts may be put to engage arms of the switch blades. At either side of the long axis of the base are the bays 20, 21, (Figs. 1 and 7) which provide ledges at the level of the upper switch blade, while midway around the well between these two bays are the bays 22, 23, each of which has a ledge 24 at the level of the lower switch blade and two ledges 25 on opposite sides thereof at the level of the upper blade.

The contacts used in bays 22, 23 are of two types. One type has wings 26 which extend to the ledges 25 and thus enable the contact portion to extend into the well at the upper blade level. The other type is like those used in the other bays 20, 21, having simply a shank that rests on the ledge 24 for support. When it is desired to have a low contact at either of the bays 20, 21 where the ledges are at the upper blade level, a contact is used that has its blade engaging portion offset downwardly from the shank which rests on the ledge. Bearing this in mind, the two sets of contacts and blades now will be described, the references to the drawings being chiefly to Figures 5 and 6.

When a three wire supply circuit is used and connections are made to all three wires, there is a short contact 31 on the ledge 24 of the bay 22 and a long contact 32 on the corresponding ledge of the bay 23 for co-action with a lower blade 30 having three long arms 33, 34, 35 and a short arm 36. It is understood that a long blade arm will engage either a long or a short fixed contact and that a short blade arm will engage only a long contact. Four upper fixed contacts are used, a short one 41 on the ledges 25 of the bay 22, a short one 42 in the bay 21, a long one 43 on the ledges 25 of the bay 23 and a long one 44 on the ledge in the bay 20. The upper blade 40 which co-operates with these has two short arms 45, 46 spaced 180° and a long arm 47 midway between them.

One outside wire A is connected with the upper short contact 41 and the other outside wire B with the lower short contact 31. The neutral wire C is connected with the upper long contact 43. The heating elements M and N are connected with the load terminals and the latter are connected with the remaining fixed contacts, as shown, the upper short contact 42 being connected with the terminal 50 which is connected with the mid-point of the elements M, N. The lower long contact 32 is connected with the terminal 51, and the upper long contact 44 with the terminal 52, these terminals being connected in turn with the outside ends of the heating elements N and M respectively.

The three degrees of heating are obtained by turning the switch blades 30 and 40 in unison from the position shown to the three other possible positions. When thus turned clockwise 90°, the heating elements M, N

are put in series across the outside wires A, B giving a high degree of heating. Another 90° turn puts the element N alone across the outside wire B and the neutral wire C to give a medium degree of heating. The low heat is obtained by another quarter turn by which the two heating elements are connected in series across the neutral wire C and the outside wire B. I make no claim to these circuit connections as they form the subject of the Nero application Serial No. 350,055, filed March 26, 1929.

When but two supply wires are used, whether two of the wires of a three wire system or the two of a two wire system, the arrangement shown in Figure 6 is preferred. The lower blade 60 has associated with it a long contact 61 on the ledge 24 of the bay 22, a short one 62 on the corresponding ledge of the bay 23 and a long contact 63 in the bay 20, the blade itself having two opposite long arms 64, 65 and a single short arm 66. There are two long upper contacts, one 71 in the bay 21, and another 72 on the ledges 25 of the bay 23. A third upper contact 73 is short and is in the bay 20. The upper blade 70 has a long arm 74 and two opposite short arms 75, 76.

The lower blade 61 and the upper blade 72 are connected respectively with the outside wire B and the neutral wire C, but may of course be connected to any other two wires of different potential. The heating elements M, N are connected with the terminals 50, 51, 52 in exactly the same way as that shown in Figure 5 and the terminals are connected with the same quarter points on the base, the terminal 50 being connected with the long upper contact 71, the terminal 51 with the lower short contact 62 and the third terminal 52 being connected with the upper short contact 73 and with the lower long contact 63 which is at the same quarter point.

When the blades of this form are turned 90° clockwise from the "off" position shown in Figure 6, the heating elements M, N are in parallel across the wires B, C for high heat. Another quarter turn puts the element M alone in circuit giving medium heat and a third turn gives the low degree of heating by putting the elements M and N in series across the same two wires B, C.

It will be observed that to change the switch so as to adapt the circuit for a two wire supply when a three wire arrangement has been in use, or to adapt some of a number of bases for the one arrangement and others for the other, it is necessary only to change the switch blades and the readily removable fixed contacts. The rest of the base is the same in either case and the connections from the base to the supply or lead wire terminals and to the load are unchanged except for the omission of the connection to the third wire

which is not used in the two wire arrangement.

As set forth above, there are three receptacle contacts opening to the bottom of the base so that an attachment plug may be used to establish the connections to the load. These receptacle contacts are the load terminals 50, 51, 52 described above. They are of a well known type needing no description here and are staggered and differently spaced so that the plug can be connected in but one position, the correct one.

The main supply wire A is received in the groove 12^a, the wire B in groove 12^b and C in 12^c. A binding post made up of a large headed screw 80 and a conductive piece 81 rests in a recess 82 in the bottom of the base, a part 83 of the piece 81 being bent in a U shape to rest in the groove 12^a. There is a 15 similar screw 85 with a like conductive piece forming a binding post or feed wire terminal in the groove 12^b. A screw 86 extends from the ledge 24 in the bay 22 through the base and threads into the conductive piece for the 20 binding post 85, thus serving to hold the binding post and the lower contact 31 in place. In like manner, a screw 84 holds the upper contact 41 and the binding post 80 in place, being threaded from above into the conductive 25 piece 81 associated with the latter.

When the two wire arrangement is used, there is no need for a wire in the groove 12^a or for an upper contact in the bay 22, hence the binding post 81 and the screw 84 described 30 above may be omitted. In this arrangement, the screw 86 holds the long lower contact 61 on the ledge 24 in place of the short contact 31 used with the three wire supply. Likewise there is a binding post 87 for the groove 12^c 35 with a securing screw 88 that holds in place the upper contact on the ledges 25 of the bay 23. Since the corresponding contacts 43 and 72 of the two arrangements are both long, this part of the device is no different for 40 either arrangement.

The connections to the receptacle contacts are made by straps resting in deep recesses on the bottom of the base and connected by screws to the appropriate fixed contacts. 45 They remain the same for both arrangements and therefore are spoken of here as being permanent connections between the load terminals and the quarter points. A strap 90 in the recess 91 is soldered or otherwise secured at one end to the clips forming the receptacle contact or load terminal 50. A screw 93 from the top of the base holds this end of the strap in the recess. At its other end, the strap 90 receives the end of a screw 94 that 50 extends through the shank of the upper level contact in the bay 21. Thus the strap 90 and the screw 94 form the connection denoted 48 in Figures 5 and 6.

Another strap 95 in a recess 96 is connected 55 to and supports the receptacle contact 52 in

a like manner and is held to the base by a screw 97. A screw 98 connects it with the contacts in the bay 21 and holds these contacts in place, forming with the strap 95 the connection denoted 49 in Figures 5 and 6. In the three wire arrangement it is the upper contact 44 that is held and in the two wire arrangement, the two contacts 63 and 73 are held by this screw 98. A short strap 99 held by a screw 100 rests in a recess 101 and supports the receptacle contact 51. This strap is connected with the lower level contact (either 32 or 62) on the ledge 24 of the bay 23 by a screw 102 which holds the said contact in place. This screw and strap form the connection denoted 38 in Figures 5 and 6. The attachment plug 103 has three blades 104 to which the lead wires from the mid-point and ends of the heating coils M, N are connected in the manner shown in Figures 5 and 6 so that when inserted into the receptacle in the base, the heating elements are properly connected with the switch contacts. A sheet 105 of insulating material is placed over the bottom of the base and has holes 106 90 to permit the blades 104 to pass through to the receptacle clips.

I claim—

1. Electrical apparatus comprising a switch base having three contacts for connection to a two-part heating device and a mounting for a rotary switch, said mounting providing four switch points, and permanent connections between said contacts and certain of said switch points, in combination with provision for mounting three feed wire terminals on said base and for connecting two or three such terminals to certain of said switch points whereby two different sets of switch contacts may be used alternatively to give three degrees of heating either with two or with three of said wire terminals conductively connected with the switch.

2. Electrical apparatus comprising an insulating block, a switch well therein with provision for mounting alternative sets of fixed contacts at quarter points about the well, provision for mounting three feed wire terminals on the opposite side of the base and for conductors extending therefrom to certain of the quarter points, in combination with receptacle contacts opening to the said opposite side and permanently connected with certain of said quarter points, for the purpose described.

3. Electrical apparatus comprising a switch base, a well therein, a rotary switch in the well, a yoke across said well for supporting the switch spindle and for mounting the base, said yoke having lateral arms adapted for fastening to said base at four equally spaced points whereby said base may be mounted in either of two positions at right angles to one another.

4. Electrical apparatus comprising a

switch base, a well therein, a rotary switch in the well, a yoke across said well for supporting the switch spindle and for mounting the base, said yoke having lateral arms adapted for fastening to said base at four equally spaced points whereby said base may be mounted in either of two positions at right angles to one another, together with receptacle contacts opening to the opposite side of said base and connected to said switch.

In testimony whereof I have signed my name to this specification.

WILLIAM H. HARRINGTON.
